VACUUM PAN DISCHARGE VALVE CONTROL

John E. Mason, Denver, Colo., assignor to The Stearns-Roger Manufacturing Company, Denver, Colo., a corporation of Colorado

Application September 7, 1943, Serial No. 501,467

1 Claim. (Cl. 137—21)

1

This invention relates to foot valves and more particularly relates to automatically operated foot valves of the type that are used in vacuum pans and the like.

In the present-day sugar refining practice, for example, there has been an increased adoption of the practice of boiling sugar solution to a high dry substance. In order to decrease the dead volume below the heating element in calandria type vacuum pans, larger foot valves are required than have been in use heretofore.

In the past, the operating mechanism used with the discharge valves has been manually actuated, but in the valve sizes now proposed to be used, manually actuated valves will be too cumbersome and difficult to operate for commercial requirements.

It is an object of the present invention to provide a simple, durable and efficient foot valve that is arranged for positive opening and closing movements.

Another object of the invention is to provide an automatic control for the foot valves of vacuum pans and the like.

A further object of the invention is to provide a simple and efficient arrangement of actuating mechanism for foot valves which insures positive seating of the valve in a succession of operations.

Other objects reside in novel details of construction and novel combinations and arrangements of parts, all of which will be described in the course of the following description.

The accompanying drawings illustrate typical embodiments of the invention. In the drawings in the several views of which like parts have been designated similarly,

Fig. 1 is a schematic arrangement of a control mechanism and associated foot valve embodying features of the present invention;

Fig. 2 is a top plan view of the foot valve of Fig. 1 drawn to an enlarged scale;

Fig. 3 is a vertical section taken along the line 3—3, Fig. 2; and

Fig. 4 is an enlarged fragmentary section illustrating the arrangement of parts of the valve assembly in the valve-seating position.

The arrangement of equipment constituting the foot valve and control will be best understood by reference to Fig. 1. A vacuum pan V has a discharge outlet extending through a rim R and a foot valve F preferably of conical shape moves through the outlet into and out of engagement with a seat on rim R under the control of a hydraulic lift L.

2

In the operation of the control mechanism, the foot valve F is moved from an open position to a closed position, and subsequently opens again to permit discharge of the pan V. While the foot valve F is in open position a pilot control switch C is placed in "automatic" position, thereby starting pump P, and the operator gradually turns a three-way control valve A, thereby opening the pump discharge line P—2 to the cylinder L and closing the line P—1 to tank T. This operation pumps oil into the hydraulic lift L with the result that foot valve F is moved into sealing engagement with the seat on rim R.

When the desired pressure is attained, pressure switch S—1 actuates magnetic switch MS which stops the motor M driving pump P and at the same time closes the solenoid operating valve O. The pressure required is variable depending on the height of the massecuite in the pan, but usually a pressure of 150 lbs. per square inch maintained at all times when the pan is "boiling" will be sufficient.

In the event the pressure drops to 130 lbs. per square inch, due to leakage or other causes, the switch S—1 immediately acts to energize the magnetic switch MS, which starts the motor M of pump P. At the same time switch S—2 opens solenoid valve O and thereafter the pump P continues in operation until such time as the pressure in the entire system again reaches 150 lbs.

At this point switch S—1 operates to stop the pump, which remains inactive thereafter until the pressure registered on a pressure gauge G has fallen to 130 lbs., which induces a repetition of the operation described hereinbefore.

Whenever the vacuum pan V is ready to be emptied, the three-way control valve A is turned manually and the pressure in hydraulic lift L is allowed to drop with the oil flowing back to a storage tank T. An orifice plate is fitted at the end of the return line to tank T and permits rapid discharge of the oil at the beginning of the return movement. The rate of oil discharge progressively decreases as the pressure of the pan contents on the foot valve F decreases.

As a consequence of this arrangement, the oil in the hydraulic lift L acts as a cushion preventing excessive shock as the piston of the lift comes to rest on the bottom of the associated cylinder. Also to permit close regulation, the opening in the orifice plate may be adjusted to give the most satisfactory operation.

The detail of the hydraulic lift arrangement will be best understood by reference to Figs. 2 and 3. The lift L comprises a casing 5 having

a cylindrical chamber 6 into which a fluid, such as oil, is admitted through an inlet 7. A hollow piston 8 is mounted for reciprocating movement in the cylinder 6 and has its top wall 8a threadedly apertured for reception of a rod 9, which may be extended to different distances within piston 8 and is held by a jam nut 10 in such selected positions.

The housing 12 adjoins the bottom of pan V and encases the discharge outlet. This housing has an inclined bottom 13 providing a chute for the discharging matter, and an opening 14 is provided at the lower end of said chute. The rod 9 extends through a bushing 15 mounted in inclined bottom 13 and a lubricant fitting 16 is mounted in the bushing for lubrication to facilitate movement of the rod 9.

The foot valve F preferably comprises a hollow conical body 17 flaring outwardly at the bottom as indicated at 18 in Fig. 3 and terminates in an inclined, double faced peripheral seating surface 19, as in Fig. 4. A series of equally spaced upstanding guides 20, here shown as three in number, are formed on the exterior surface of valve F and engage the sides of rim R during movements of the valve.

On the interior of valve F a central socket member 21 is formed integrally or fixedly held thereon for reception of a ball member 22 carried at the end of rod 9. This ball and socket joint provides a self-adjusting action when the valve F is seating against rim R which is further assisted by the action of guides 20 which bear against rim R throughout the entire range of the opening and closing valve movements, and by a cap 21a which holds member 22 in position and allows a limited free movement of valve F.

In order to provide a satisfactory seat and seal, the rim R preferably is formed as an annular body and welded to the vacuum pan V as shown at 23 in Fig. 4. The surfaces of the discharge outlet thus formed are shaped to conform to the double faced seating surface 19 of the valve. A dovetail recess 24 is formed in the lower seating surface of rim R and a ring 25 fitted against a shoulder 26 on the bottom of the rim clamps a resilient gasket 27 into the recess.

This gasket provides a sealing action when the valve is moved to closed position and the conforming surfaces of the valve and rim are in such a close fit that no escape of matter from the vacuum pan is permitted when the valve is seated in the opening.

This design and arrangement of parts satisfies the requirements of modern industrial practice. Larger foot valves may be provided for the calandria type and coil type vacuum pans than could be utilized if the control was dependent upon manual actuation. The provision of the hydraulic system for valve actuation insures prompt valve opening and closing movements, and the cushioning action in the piston return prevents damage to the lift structure, which otherwise might present a repair and replacement problem.

The mounting of the gasket on the underside of rim R permits periodic replacement without undue loss of time, and also increases the life of the gasket, due to the discharging material flowing over the valve F and rim R but usually around the gasket to a greater or lesser degree. Thus, the gasket is in a flow protected position. The adjustment of the rod on the lift piston permits a substantial variation in the valve

stroke, and the ball and socket joint in cooperation with the design features of the rim and valve insures perfect seating in each valve operation.

The provision of the housing about the lift structure eliminates a difficulty heretofore existent in the art caused by the escape of steam into the factory building and resultant corrosion occasioned by "steaming out" of the pans.

The arrangement of control mechanism has the advantage of providing regulation for a single foot valve or a plurality of such valves. In Fig. 1, the three-way valve A is the control means for the foot valve F, and if a series of such valves are to be operated by the control, other three-way valves A-1 and A-2 would regulate similar valves F (not shown). In such event, the three-way valve could be located where the individual discharge lines join and preferably this valve, the motor switch C and the pressure gauge G will be located at the most convenient place on the vacuum pan for access by the operator.

What I claim and wish to secure by Letters Patent is:

A discharge control for a plurality of vacuum pans and the like, which comprises a bottom for each pan and having an opening providing a discharge outlet; a foot valve mounted beneath each pan for vertical movement into and out of sealing engagement with the respective outlet; a hydraulic lift connected with each foot valve for elevating said valve into sealing engagement with the outlet; a source of fluid under pressure; a discharge line; a separate line leading to each hydraulic lift; a plurality of three-way valves, each connected with a lift line and also with said pressure and discharge lines, said valves being movable to a position connecting the respective lift line with said pressure line, and to a second position connecting the respective lift line with said discharge line; means associated with said pressure line for maintaining fluid pressure therein at or above a predetermined value; and flow restricting means in said discharge line for restraining the initial opening movement of a lift valve when the three-way valve associated therewith is turned to a position connecting the respective lift line with discharge line.
